UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

FURNACE PROTECTION.

1,143,284.

Specification of Letters Patent. Patented June 15, 1915.

Application filed July 6, 1914. Serial No. 849,163.

To all whom it may concern:

Be it known that I, LUTHER L. KNOX, a citizen of the United States, residing at Avalon, in the county of Allegheny and State of Pennsylvania, have invented a new and useful Improvement in Furnace Protection, of which the following is a full, clear, and exact description, reference being had to the accompanying drawings, forming part of this specification, in which—

Figure 1 is a front elevation of a furnace having my invention applied thereto. Fig. 2 is a section on the line II—II of Fig. 1. Fig. 3 is a section on the line III—III of Fig. 1. Fig. 4 is a plan view, Fig. 5 is a front elevation, and Fig. 6 is a vertical section of a combined apron and air box.

In the operation of certain furnaces, such for instance as sheet and pair furnaces, the workmen are required to perform certain operations in the way of manipulating metal being heated through open or partially open furnace doors. While performing these operations they are without adequate protection from the intense heat escaping through the doors.

My invention is designed to provide a water cooled shield for furnaces of this character, and which is so constructed and arranged that it will form an efficient means of protection for the workmen.

My invention also provides safety guards or aprons for preventing injury to the workmen from the counterweights employed in the operation of the furnace doors and dampers and it also provides a novel form of air reservoir in connection with one of these aprons or guards, whereby the workmen can blow air upon themselves as may be desired while at work about the furnace.

In the accompanying drawings, I have shown my invention as applied to a sheet and pair furnace and the arrangement shown will now be described.

2 designates a portion of the walls of the furnace, 3 the compartment in which the sheets are heated, and 4 the pair heating compartment or side of the furnace.

5 is the usual low door opening leading into compartment 3; and 6 is a similar opening leading into compartment 4.

7 indicates the usual vertically movable doors for controlling the openings 5 and 6 to which are attached the counterweights 8.

In accordance with my invention, I provide water cooled shields such as shown at 9, these shields being arranged to partially cover the door openings 5 and 6 in front of the doors 7. I preferably form each of these shields of a simple blank of sheet metal 60 bent upon itself into general U-shape, as shown in Fig. 3, and having a top closing flange 10 welded at one of the upper corners 11 of the shield. The shield therefore consists of a closed flat hollow box, which is designed to be filled with water which is circulated therethrough. This water may be supplied by an inlet pipe 12 which is arranged to telescope on a supply pipe 13. In the drawings I have shown only one of the 70 shields as provided with a supply connection, the other shield being supplied by the overflow from the first shield through a flexible connecting hose 14. Each shield is preferably provided with a constantly open vent 75 15 leading out of its upper portion to permit the free escape of any steam which may be formed. The second shield is also provided with an outlet connection 15^a for the heated water.

The shields are supported in place in any suitable manner as by the hanger bars 16 which are secured at their upper ends to the top frame member 17 of the furnace frame.

The shields are set outwardly away from the end of the furnace on the buckstays 18, as best shown in Fig. 2, so as to provide a sufficient space behind the shields and between the shields and the doors 7 for the hot air and products of combustion from the 90 furnace to pass upwardly behind the shields. In this manner the heads and faces of the workmen are protected.

20 designates counterweights for operating the usual dampers (not shown). These 95 counterweights are attached to the cables 21 which pass upwardly and over the wheels or pulleys 22. In order to prevent injury to the workmen from the counterweights 8 and 20, I secure to the front of the furnace the 100 hollow aprons 23, 23^a and 24. These aprons form pockets within which the counterweights work. The central box 24 between the two furnace doors is preferably divided into two compartments by a vertical partition 24^a. The outer compartment 25 is closed except for the provision of an air supply pipe 26 and the two outlet connections 27.

at the top. Each of these connections has an elbow shaped nozzle 28 rotatably secured therein.

The workman can move either one of these 5 nozzles at any desired angle to cause air to be blown upon him wherever desired. The inner compartment 29 of the central apron acts as a pocket for the counterweight 20.

My invention provides means of simple 10 character which protects the workmen while engaged in the necessary furnace operations.

I claim:

1. The combination with a furnace having a door opening and a vertically movable 15 door for said opening, of a water cooled shield supported across the upper portion of said opening in front of the door; substantially as described.

2. The combination with a furnace having 20 a door opening and a vertically movable door for said opening, of a hollow shield supported across the upper portion of said opening in front of the door, and means for maintaining a water circulation through 25 said shield; substantially as described.

3. The combination with a furnace having a door opening and a vertically movable door for said opening, of a hollow shield supported across the upper portion of said 30 opening in front of the door, and means for maintaining a water circulation through said shield, said shield being separated from the end of the furnace to provide a space behind it for the upward passage of hot air 35 and products of combustion escaping from the furnace door; substantially as described.

4. The combination with a furnace having

adjacent door openings and vertically movable doors for said openings, of water cooled shields supported one across the upper portion of each opening in front of said doors, a water supply connection for one of said shields, an outlet connection for the other shield, and a circulating connection between the two shields; substantially as described. 40

5. The combination with a furnace having movable parts, and counterweights for said parts arranged at the end of the furnace, of aprons inclosing said counterweights and forming safety pockets therefor; substantially as described. 50

6. The combination with a furnace, of an air chamber adjacent thereto, said chamber having a swiveled air discharge nozzle arranged to discharge air from said chamber in various directions; substantially as described. 55

7. The combination with the end wall of a furnace, of a guard chamber or pocket adjacent thereto, said chamber or pocket having two compartments, means for introducing or discharging air from one of said compartments, and the other compartment forming a guard pocket for the damper counterweights of the furnace; substantially as described. 60 65

In testimony whereof, I have hereunto set my hand.

LUTHER L. KNOX.
